UNITED STATES PATENT OFFICE.

HERMAN W. SCHATZ, OF CINCINNATI, OHIO, ASSIGNOR TO THE AMERICAN TOOL WORKS COMPANY, OF CINCINNATI, OHIO, A CORPORATION OF WEST VIRGINIA.

VARIABLE-SPEED MECHANISM.

No. 918,773.

Specification of Letters Patent.

Patented April 20, 1909.

Application filed December 28, 1908. Serial No. 469,571.

To all whom it may concern:

Be it known that I, HERMAN W. SCHATZ, a citizen of the United States, residing at Cincinnati, in the county of Hamilton and State of Ohio, have invented certain new and useful Improvements in Variable-Speed Mechanism, of which the following is a specification.

My invention relates to an improvement in the feed mechanism for a machine tool.

The object of the invention is to provide an ample range of feeds within a compact compass, and preferably within a feed box in which the parts can be conveniently and cheaply assembled, and then bolted as a unit to the frame.

Another object of my invention is to provide an arrangement of such a wide speed range, that it will satisfy all of the requirements in this direction, without having to depend upon speeds derived from the compound effect of several variable speed systems disposed at different points in the machine organization, as is commonly done in standard tools of today.

Another object of the invention is to provide a feed-box and a change gear system adaptable without substantial modification, to the requirements of either of the metric or domestic scales.

The features of the invention are more fully set forth in the description of the accompanying drawings, forming a part of this specification, in which:

Figure 1 is a central vertical section through my improvement. Fig. 2 is a sectional view through the shifting tumbler mechanism. (Figs. 1 and 2 illustrate the gearing arrangement for a metric system.)

Fig. 3 is a side elevation of my improvement as applied to a lathe and in an arrangement for a domestic system. Fig. 4 is a front elevation of the same. Fig. 5 is an enlarged section on line *v*, *v*, Fig. 3. Fig. 6 is a section on line *x*, *x*, Fig. 5. Fig. 7 is a section on line *u*, Fig. 6. Fig. 8 is a section on line *w*, Fig. 5.

Fig. 9 is a section on line *a*, *a*, Fig. 6. Thus it will be seen that Figs. 1 and 2 represent the metric system and the remainder the domestic system.

1 is the feed-box in which is journaled within suitable bearings the tumbler shaft 2.

3, (Fig. 7—the domestic system), is the gear fixed on shaft 2, outside of the box, 55 driven by the train of gears 4, 5, the latter

being an intermediate in the train and adjustable on the quadrant 6, gears 3 and 4 are made removable thus permitting of change gear mountings if desired.

Upon shaft 2 is mounted the ordinary tumbler 7, projected through the casing slot 8, said tumbler carrying the pinion 9, sliding on and turning with shaft 2, and the gear 10 for driving the cone.

11 represents the cone bearing shaft 65 mounted in suitable bearings formed in the box 1.

12 is the cone of gears in the metric system, (Fig. 1); it is fixed to sleeve 13 loose on shaft 11. In the domestic system, (Fig. 5), 70 12 is the cone of gears in the metric system, (Fig. 1); it is fixed to sleeve 13 loose on shaft 11. In the domestic system, (Fig. 5), 70 the cone is fixed directly to shaft 11.

14, 15, is the compound gear member, the gears being spaced apart and connected by a sleeve. In the metric system, (Fig. 1), it is fixed directly to shaft 11, and in the domestic system, (Fig. 5), it is fixed to a sleeve 75 26, loose on shaft 11, 40 being a gear on the outer end of this sleeve 26 for transmitting the motion from the variable speed box.

In the metric system (see Figs. 1 and 2) the 80 driving gear 3^a is on the outer end of shaft 11, the driven element being the tumbler shaft 2. In the domestic system (see Figs. 5 and 7), the driving gear 3 is on the tumbler shaft 2 and the sleeve 26 is the driven element. 85

It is to be understood that in the standard domestic system of screws there are so many threads to the inch, while in the metric system the threads have standard millimeter pitches. The pitch of the lead screw will be 90 different in domestic and metric system lathes. In the domestic system illustrated herein, the driver being the tumbler shaft and sleeve 26 the driven element, will give a different ratio of speeds between the spindle and lead screw than is obtainable from the metric system, in which, the member 14, 15, is the driving element and the tumbler shaft the driven element.

My invention has important manufacturing advantages in that the parts and the organization are substantially the same in both systems, except that in assembling the relationship of the driving and the driven members is changed by selecting which shall 100 be the fixed and which the loose gears and by transposing the relationship of the driving and driven members, which matters will be readily understood, by mechanics skilled in the art, from this description. Thus it is ap- 105 110

parent that the organizations are the same in principle for the metric and domestic systems, and only differ in the order of the drive, and the relative fixidity and looseness of the 5 elements on shaft 11, in one case the cone of gears being loose on the shaft with the compound gear member fixed to said shaft, while in the other case the cone is fixed to the shaft while the compound gear member is loose on 10 the shaft. The cone is always an intermediate element of both systems, that is, compound gear member 14, 15, is the driver in Fig. 1, the tumbler the driven and the cone an intermediate element of the train; in Fig. 15 5, the tumbler is the driver, compound gear member 14, 15, the driven and cone 12 an intermediate element of the train. 16 represents a counter shaft journaled in suitable bearings formed in the box. Upon it is 20 mounted gear 17, formed with a sleeve 18, having the end clutch teeth 19; gear 17 meshing with the smallest gear of the cone. 20 represents a gear formed with the sleeve 21, having clutch teeth 22. Said gear 20 meshing with the largest gear of the cone. Sleeves 18 and 21 are loose relative to shaft 16, but may be alternately fixed thereto, by shifting the double clutch member 23, fixed to shaft 16, intermediate the clutch members 30 19, 22.

24, 25, represents a compound gear member splined directly to shaft 16, with the member 24, adapted to be meshed with the gear 15, on shaft 11, and the gear 25, adapted 35 to be meshed with the gear 14, on shaft 11.

In operation, it will be understood, that the tumbler is manipulated in the usual way to engage gear 10 selectively with the individual members of the cone 12. Assume the 40 tumbler gear 10 is intermeshed with a selected gear of the cone, if now, clutches 19, 23, are engaged, and gears 24, 15; shaft 11 is driven at one speed; if now, gears 25, 14, are engaged, another speed is obtainable with the tumbler in the same position. 45

For shifting the clutch 23 and the compound sliding gears 24, 25, I provide the rock arms and rock shaft mechanism 28, having the handle detents 29, in usual form, 50 properly indexed. If now, clutch members 22, 23, be engaged, the splined compound gear members 24, 25, may be shifted relative to gears 14, 15, to derive two more speeds, so that four different speeds are thus derived from the system with the tumbler in a fixed position. Of course, by the recourse to the tumbler system, a range of speeds may be obtained equal to four times the number 55 of gears comprised in the cone.

60 As an additional convenience of this box, it will be observed that the three levers for manipulating the tumbler, slide-gear and slide-clutch elements project conveniently from the front of the box in position to be

admirably indexed and to be easily manipulated by the operator in his customary position with reference to the tool. 65

Having described my invention, I claim:—

1. A pair of shafts, a cone of gears and a second gear member, one member being 70 loose the other being fixed on the first shaft, a pair of gears loose on the second shaft and intermeshed with two of the gears of the cone, means for clutching said gears alternatively to the second shaft, a third gear 75 member fixed to the second shaft and meshing with the second gear member of the first shaft, a tumbler shaft and a tumbling gear driven therefrom adapted to intermesh with the gears of the cone. 80

2. A pair of shafts, a cone of gears and a second compound gear member, one being loose and the other being fixed on the first shaft, a pair of gears loose on the second shaft and intermeshed with two of the gears 85 of the cone, means for clutching said gears alternatively to said second shaft, a third compound gear rotatively fixed to the second shaft its elements being adapted to be intermeshed selectively with the elements of the 90 second compound gear member of the first shaft.

3. A pair of shafts, a sleeve loose on the first shaft, a cone of gears and a second compound gear member, one being fixed on the 95 sleeve and the other on the first shaft, a pair of gears loose on the second shaft and intermeshed with two of the gears of the cone, means for clutching said gears alternatively to said second shaft, a third compound gear 100 member fixed to the second shaft its elements being adapted to be intermeshed selectively with the elements of the second compound gear member of the first shaft, substantially as described. 105

4. A pair of shafts, a sleeve loose on the first shaft, a cone of gears and a compound gear member one being fixed on the sleeve and the other on the first shaft, a pair of gears loose on the second shaft and intermeshed with two of the gears of the cone, means for clutching said gears alternatively to said second shaft, a third compound gear member fixed to the second shaft its elements being adapted to intermesh respectively with the elements of the second compound gear member of the first shaft, and means for shifting one of the said compound gear members to make alternative intermeshes whereby four speeds may be taken 110 from each element of the cone. 115

In testimony whereof, I have hereunto set my hand.

HERMAN W. SCHATZ.
